ELECTRIC CONTROLLED SPOTLIGHT

Filed Nov. 2, 1927

*Inventor,
Anthony Caminetto, Jr
George J. Henry
By Attorney*

UNITED STATES PATENT OFFICE.

ANTHONY CAMINETTI, JR., OF SAN FRANCISCO, CALIFORNIA.

ELECTRIC CONTROLLED SPOTLIGHT.

Application filed November 2, 1927. Serial No. 230,397.

My invention has for its object a dirigible spotlight adapted to use on vehicles; and incorporated therewith is mechanism and means for automatically preventing or cutting out the illumination of the light over a selected area of projection for the purpose of preventing the blinding effect on others in front thereof, while emitting full illumination over other portions of the projected area within the range of lamp movement.

Other objects will appear from the drawing and specifications which follow.

These objects I attain by mounting in co-operation with movable portions of the mechanism, electric conducting and switching means whereby upon a directive movement within a predetermined range the electric conductivity to the lamp is interrupted.

By referring to the accompanying drawing my invention will be made clear.

In the drawing:

Fig. 1 is a side view of my spotlight mounted upon the forward portion of a conventional automobile.

Fig. 2 is a plan view of Fig. 1.

Fig. 3 is a plan view of Figs. 1 and 2 when the lamp is tilted to project a beam above the horizontal plane 12, the lamp being shown in full lines when turned to the left and in dotted lines when turned to the right.

Fig. 4 is a fragmentary showing of the upper portions of my lamp and with the switching and operating means shown in section.

Fig. 5 is a part view and part section of the parts shown in Fig. 4 and at right angles thereto.

Figs. 6 and 7 are side view details of the electric switching means and its operation.

Figs. 8 and 9 are plan views of Figs. 6 and 7 respectively.

Figs. 10 and 11 are details of the switch parts.

Fig. 12 is a view of a wall in front of the vehicle of Fig. 1 showing by the dark area those portions which are obscured throughout the range of lamp operation and by the light portion is indicated the area which may be covered by the full range of spotlight movement.

Throughout the figures similar numerals refer to identical parts.

A conventional vehicle is shown by the

numeral 1 on which is mounted my spotlight 2, adapted to swing through a vertical range shown by the angle 3 and through a horizontal range indicated by the angle 4. 60

The lamp 2 is adapted to project a single beam which illuminates the roadway in front of the vehicle as shown at 5 when the lamp is turned to the left, and as shown at 6, when turned to the right, and any single 65 portion of the roadway in front below the plane 12, but is prevented from any possible illumination of the center field above the plane 12.

The lamp is supported from the arm 7 70 and is adapted to swing about the horizontal pivotal axis 8, and also about the vertical axis 9, thus having a range of universal movement.

The lamp casing at 10 is adapted to contain any conventional source of illumination as the incandescent lamp 11 and suitable reflecting means not shown in detail but well known.

It is desirable in a spotlight of this character to prevent a glaring projection in front of the vehicle which would have a blinding effect upon other drivers, whereas it is very desirable to have side road illumination when desired as at 5 or 6, and 85 central road illumination below the horizontal plane 12 and within the range of the angle 3.

The incandescent lamp or light source 11 is energized by the conventional battery 13 90 through the brush 14, insulated pin 15 and thence to the contact arms 16, 16, the other pole of the battery being grounded as at 17, and the other side of the lamp being grounded at 18.

Mounted upon the lamp casing 10 and insulated therefrom is the rack 19 carrying an insulating portion 20.

The contact arms 16, 16 are pivoted at 21 and are normally held in the position shown 100 in Fig. 7, by the spring 22 such that they ride upon the metallic surface of the rack 19 throughout its entire range of movement about the axis 9, whenever the lamp is directed to either side to cast the beams 5 or 6 or whenever it is tilted downward below the plane 12.

However, when the lamp is directed forward above the plane 12 the contact arms ride upon the insulation 20, the circuit is interrupted and the lamp is not illuminated unless the lamp is rotated about the vertical

axis 9 to the right or left so as to come within the beam range 5 or 6 in which case full illumination during the tilting of the lamp on the axis 8 is attained.

5 The possible projected area within any portion of which the spotlight beam may be directed against a vertical plane is therefore as shown in Fig. 12 at 5, 6 and 41 while the dark portion 40 is that over which the projected beam will be automatically cut out. This action takes place through the insulating block 30 riding against the pin 31 when the beam is directed straight forward and above the plane 12 causing the contact arms to swing from the position shown in Fig. 7 into the position shown in Fig. 6, when, due to their riding upon the insulating member 20 the lamp is cut out. This movement is best shown in Figs. 8 and 9. 10 The pin 31 being upon fixed portions of the bracket 7 is in the path of movement of block 30 as the lamp is rotated about the vertical axis 9, so that when the lamp is turned to either side as shown in Fig. 9 15 the block 30 riding free of the pin 31 enables the contact arms to maintain the circuit through the rack 19 as shown in Fig. 7, whereas when the lamp is directed straight ahead and above the plane 12, the block 30 20 riding upon the pin 31 forces the contact arms downward on to the insulated member 20 interrupting the circuit as shown in Figs. 6 and 8.

The range of projected beam illumination will therefore be as shown in Fig. 12 at 5, 6 and 41 and the dark portion 40 directly in front of and above the plane 12 corresponds with the range within which approaching vehicle drivers are protected 25 from any glare from the spotlight by the automatic dimming of the lamp within this latter range of movement, whereas the oper-

ator of the vehicle 1 may employ the lamp freely over any portion of the side areas 5 and 6 securing any specific side illumination desired in lamps of this character and also may secure additional illumination throughout the central road surface and objects thereon below the plane 12 as shown at 41.

50 It will now be apparent that changes in the details of construction and variations in the circuit connections may be employed without departing from the spirit of my invention and I wish to be understood as 55 claiming such variations, the mechanism which I have here described being but one of the preferred forms of my invention.

I claim:

60 A dirigible spot lamp comprising an energizing circuit and a lamp positioned within a light projector casing, said casing mounted on a pivotal axis in a frame, said frame rotatably mounted on a support and on an axis at right angles to said pivotal 65 axis, in combination with switch means interposed in said circuit and comprising a lever of the first order pivotally mounted on said frame, spring means normally retaining said lever in a predetermined position, 70 a trip on said support against which one end of said lever brushes thereby forcing said lever out of said position when the frame is within a predetermined range of movement, a contact block carried by said 75 casing and normally engaging the other end of said lever said block having an insulating portion positioned to break circuit with said lever only when the casing is moved within a small portion of its range 80 on said first named pivotal axis while said trip is in engagement with said other end of said lever.

ANTHONY CAMINETTI, JR.
